[57] CLAIM

The ornamental design for removable stop for a paint roller handle, as shown and described.

DESCRIPTION

FIG. 1 is a top plan view of the removable stop for a paint roller handle showing my new design;
FIG. 2 is a bottom plan view thereof;
FIG. 3 is a front elevational view thereof;
FIG. 4 is a side elevational view, the opposite side being identical thereto;
FIG. 5 is a rear elevational view thereof.

FIG. 1

FIG. 2

FIG. 3

FIG. 4

FIG. 5
